UNITED STATES PATENT OFFICE.

ALDEN M. DRAKE, OF WORCESTER, MASSACHUSETTS, ASSIGNOR TO HEALD MACHINE COMPANY, OF WORCESTER, MASSACHUSETTS, A CORPORATION OF MASSACHUSETTS.

MAGNETIC CHUCK AND CASING.

1,213,167.

Specification of Letters Patent. Patented Jan. 23, 1917.

Application filed September 26, 1916. Serial No. 122,304.

To all whom it may concern:

Be it known that I, ALDEN M. DRAKE, a citizen of the United States, residing at Worcester, in the county of Worcester and State of Massachusetts, have invented a new and useful Magnetic Chuck and Casing, of which the following is a specification.

This invention relates to a magnetic chuck and to a casing therefor adapted to 10 exclude water and cutting compounds from the interior of the chuck body. Soda water and cutting compounds are used in large quantities in grinding operations and not infrequently find their way into the interior 15 of the magnetic chucks, where they cause serious damage by short-circuiting the coils and destroying the insulation.

It is the object of my invention to provide an improved combination of magnetic chuck 20 and casing by the use of which all fluids may be effectively excluded while at the same time the construction is simplified and low cost of manufacture is attained.

With this object in view an important feature of my invention relates to the provision of an outwardly projecting flange on the cover plate of the chuck to which a casing may be securely clamped, with surface engagement between the flange and the casing. 30 In the preferred form I also provide a band engaging the opposite face or surface of the flange and I provide means for drawing the casing and band together thereby securing a tight bearing at all points of the circumference on both parallel surfaces of the flange.

My invention further relates to certain arrangements and combinations of parts which will be hereinafter described and more particularly pointed out in the appended 40 claims.

A preferred form of my invention is shown in the drawing which is a vertical sectional view of a magnetic chuck and casing embodying my invention. The chuck, 45 as shown in the drawing, is formed in two parts, a body portion 10, and a top or cover plate 11, these parts being secured together by suitable screws 12. This type of chuck is frequently mounted upon the upper end of a spindle 13 rotatable in a bearing 14. Suitable provision, not shown, is made for rotating the chuck, and a casing 15 is secured thereto to exclude cutting compounds or other fluids from the interior of the body 10. 55 Upwardly-extending circular flanges 16 and

17 may be formed integral with the bearing 14 and positioned adjacent the casing 15 on the inner and outer sides thereof respectively. With this construction it will be seen that it is impossible for fluids to reach the interior of the chuck except by passing through the joint between the casing 15 and the chuck. In order to prevent any leakage at this point I provide an annular flange 20 upon the outer edge of the cover plate 11. As shown in the drawings this flange is formed at the lower edge of the plate, and in any event it should be located at a substantial distance below the working surface of the chuck. The parallel surfaces of this flange are carefully finished and the inwardly extending portion 15^a of the casing 15 is also machined to form a close fit upon the flange 20. It is particularly important that the casing 15 closely engage the upper 75 surface of the flange 20, and in the preferred form the casing also fits closely against the curved edge of the cover plate 11, and against the curved edge of the flange 20. A ring or band 21 is fitted under 80 the flange 20, and is provided with a number of tapped holes adapted to receive binding screws 22 which extend down through the portion 15^a of the casing 15. By turning these screws the band 21 and the portion 15^a 85 may be drawn tightly against the opposite sides of the flange 20, thus forming a close fitting joint which effectually excludes moisture and fluids from the interior of the body 10. 90

This construction, though simple in its details, has been found peculiarly effective for the purpose for which it is designed.

Having thus described my invention, it will be evident that changes and modifications may be made therein by those skilled in the art without departing from the spirit and scope of my invention as expressed in the claims, and I do not wish to be otherwise limited to the details herein disclosed, but 95

What I claim is—

1. In combination, a magnetic chuck and a casing therefor, said chuck comprising a body member and a top plate suitably secured to each other, said top plate having a flange projecting outwardly therefrom at a point below the upper surface thereof, and said casing comprising a cover member encircling said top plate and engaging said flange and having a depending outer por- 105 110

tion, and means to clamp said member firmly against said flange, whereby a tight joint is formed.

2. In combination, a magnetic chuck and 5 a casing therefor, said chuck having a top plate with a flange below its upper surface, and said casing comprising a cover member having an inwardly projecting portion fitting the upper surface of said flange, a band 10 engaging the lower surface of said flange, and means to draw said cover member and band firmly against the parallel faces of said flange, forming close contact therewith.

3. In combination, a circular magnetic

chuck and a casing therefor, said chuck having a top plate with a flange projecting outwardly therefrom below its upper surface, and said casing comprising a cover member having an annular inwardly projecting portion engaging the upper and outer surfaces 20 of said flange and having a depending cylindrical outer portion spaced from said chuck, a band engaging the lower surface of said flange, and means to draw said annular portion and band firmly against said flange. 25

In testimony whereof I have hereunto affixed my signature.

ALDEN M. DRAKE.
